APPARATUS FOR MAKING WALL BOARD

Original Filed May 10, 1926

Inventor
Caleb Payne
By Wm. O. Bell Atty.

UNITED STATES PATENT OFFICE.

CALEB PAYNE, OF CHICAGO, ILLINOIS, ASSIGNOR TO GYPSUM ENGINEERING AND MANUFACTURING CO., OF CHICAGO, ILLINOIS, A CORPORATION OF ILLINOIS.

APPARATUS FOR MAKING WALL BOARD.

Original application filed May 10, 1926, Serial No. 107,854. Divided and this application filed August 22, 1927. Serial No. 214,577.

This is a division of my application Serial No. 107,854 filed May 10, 1926.

The primary object of the invention is to manufacture a wall board of superior insulating quality which is light in weight and strong and substantial in structure.

Another object of the invention is to form a continuous strip of protective material into a trough which moves continuously, as it is formed, in upright position and open at the top to receive foamaceous material which fills the trough and produces a cellular body, the product being cut and dried in lengths suitable for shipping.

And a further object of the invention is to form the body of the wall board in a trough of protective covering and then seal the edge of the trough by depositing a sealing material therein.

In the accompanying drawings illustrating diagrammatically a selected embodiment of the invention:

Fig. 1 is a sectional view of wall board made in accordance with my invention.

Fig. 2 is an elevation, partly in section, showing diagrammatically an apparatus which may be employed for manufacturing wall board on edge in accordance with my invention.

Fig. 3 is a similar view of additional apparatus which may be employed in connection with that shown in Fig. 1 for sealing the open edge of the wall board.

Figs. 4 and 5 are sectional views on the lines 4-4 and 5-5 respectively of Fig. 1.

Fig. 6 is a longitudinal sectional view of a portion of the board and means for protecting the raw edge of the board.

Fig. 7 is a detail sectional view.

I contemplate using as a protective covering for my wall board the kind of paper which is now generally used for this purpose in separate sheets to form the sides of wall board. I prefer to provide the paper in a

roll 6 from which it is drawn in the form of a strip or web 7 and folded by suitable means into a trough 8, Fig. 4, open at the top to receive the body material. A presser roller 9 and a former 9' may be provided for fold-

ing the web into a trough which travels open edge upward through a pouring frame 10. This frame has a plurality of vertically dis-

posed rollers 11 arranged close together in two parallel series between which the paper trough travels while it is receiving from a supply receptacle 12 the material for making the body 13 of the wall board. The pouring frame is of a length to maintain the trough in upright position for a sufficient time after the body material is poured thereinto for the body material to set to an extent which will permit the further treatment of the board. The two series of rollers are spaced apart to produce a board of desired thickness and they are of relatively small diameter and are set comparatively close together to form a sufficiently continuous support on each side of the paper trough to maintain the trough in upright position while the body material is being poured therein and while the body material is setting sufficiently to enable the board thus formed to be further treated.

I contemplate using a foamaceous material for making a light weight cellular body for the board. The material is of a pouring consistency and is permitted to pour from the receptacle 12 into the trough at or about the front end of the pouring frame. This material is of a character which will be converted into foam after it enters the trough, and in foaming the material is distributed in a substantially uniform manner in the trough from top to bottom thereof to form a cellular body of uniform cellular structure and uniform thickness. The body sets and becomes self supporting progressively in the trough and, if desired, the space between the rollers may be progressively increased to correspond with the progressive setting of the body material; but adjacent the pouring front end of the pouring frame the rollers should be set close together to support the trough in proper position with parallel sides and to prevent deformation of the sides.

When the board is discharged from the pouring frame it may be cut by a suitable cutter 14 into predetermined lengths 15 which pass from the cutter to a guide 16 of suitable construction, which turns each length 15 from an upright to a horizontal position for convenience in running it through the drier 17. This drier may be of any suitable kind and it is preferably provided with a plurality of passes into which the lengths

may be directed by means familiar in the arts to increase the capacity of the drier since it is contemplated that the board will travel through the drier at a slower rate of speed than the trough will travel through the pouring frame and the board lengths will be cut.

The wall board thus formed will be of a specified width, length and thickness; both sides of the board will have a protective covering of paper and one long edge, the bottom of the trough, will have a paper covering. But the upper long edge, the top of the trough, will be raw; that is to say the body will be exposed. Such a board may be satisfactory for some purposes, but I prefer to protect this raw edge so that it will be as well finished for commercial purposes as the other long edge, and so that it will be uniformly straight and parallel with the other long edge. To this end, the pouring frame may be provided at the top with means, such as a strip 19, Fig. 5, to fit within the trough at the top thereof and form a guide for the upper edges of the paper covering and a wall to form the edge of the body at the open end of the trough. This strip 19 may be located to permit the body to form flush with the upper edges of the trough covering, but I prefer that the strip should project into the trough so that the upper edge of the body will be located slightly within the trough and below the upper edges of the sides of the trough, leaving a recess extending longitudinally of the board along the edge thereof and between the edges of the paper covering on the sides of the board. It is this recess which I fill with a material to protect the edge of the body and the edges of the paper sides of the board. The filling material may be compo pulp made of paper pulp and a binder or any other material suitable for the purpose.

When the board length leaves the drier 17, Fig. 3, in a horizontal position, it is turned to an upright position by a suitable guide 20 with the raw edge of the board up. Then the board passes under the discharge end of a receptacle 21 which contains the compo pulp or other filling material and this material is deposited in the recess at the upper edge of the board. A smoother 22, Fig. 6, is supported above the board and adjacent the receptacle 21 to remove surplus filler and to smooth the filler which is deposited upon the board. It is desired that the material set quickly to fill the recess and to form a protective covering 23 for what would otherwise be a raw edge of the board. I may provide for depositing the filler on the board to form the protective strip 23 between the pouring frame and the cutter, or between the cutter and the drier, and the filler may be deposited while the board remains in the pouring frame, the latter frame being extended if found necessary or desirable for the purpose and the re-

ceptacle 21 and the smoother 22 would then be mounted on or above the pouring frame or adjacent thereto.

My invention provides for the manufacture of a novel wall board which is light in weight, has superior insulating quality, and is capable of being made in standard or special sizes. I estimate that wall board made in accordance with my invention will weigh approximately one-third of the weight of corresponding commercial wall board at present in use, and this is of special importance in structural material because it enables wall board to be satisfactorily used in large sizes. A wall board of large size made in accordance with my invention will permit of handling without distortion or liability of being damaged and hold its shape to an extent and in a manner which is not possible under ordinary conditions with wall board of the kind at present manufactured. This is because it is so much lighter in weight for a given size than present commercial wall board. And its advantages in this respect increase with the increase in thickness as well as with the increase in area of the wall board being used. The wall board of my invention has superior insulating quality because of the cellular character of the body of the board; and while this cellular body may appear to be of delicate and fragile structure, it has sufficient strength when protected by a covering of paper or other suitable material, as contemplated by my invention, to be capable of use for such purposes as wall board may be used and to better advantage and with better results than wall board of present manufacture.

I have not attempted to show any means for drawing the covering material from the roll 6 or any means for moving the trough and the board through the pouring frame, the drier and the other parts of the apparatus, or other means, more or less necessary in connection with the apparatus, and which are now in use in different forms for different purposes and can be purchased in the open market or built as required and which form no part of the present invention.

Instead of providing compo pulp or other similar material for sealing the raw open edge of the trough, I may make one side of the trough wider than the board to be produced and then fold the projecting margin 24, Fig. 7, down upon the raw edge of the board and affix this margin to the body so that the body will be protected by the one strip of covering upon both sides and upon both edges. Any adhesive material may be used for affixing the margin 24 to the body, if this adhesive is found to be necessary or desirable.

I am aware that changes in the form, construction and arrangement of the apparatus and in the materials used and in the structure of the wall board may be made without departing from the invention and I reserve the

right to make all such changes as fairly fall within the scope of the following claims.

I claim:

1. Apparatus for making wall board with foamaceous material which comprises means for folding a strip of covering material into a continuous forwardly travelling narrow trough, means for supporting said trough in upright position, its long closed edge being down and its long open edge up, and means for pouring body material into said trough through the long open top edge thereof.
2. Apparatus for making wall board with foamaceous material which comprises means for folding a strip of covering material into a continuous forwardly travelling narrow trough, means for supporting said trough in upright position, its long closed edge being down and its long open edge up, means for pouring body material into said trough through the long open top edge thereof, and a drier aligned with the board forming means to receive the board as it leaves the forming means.
3. Apparatus for making wall board with foamaceous material which comprises means for folding a strip of covering material into a continuous forwardly travelling narrow trough, means for supporting said trough in upright position, its long closed edge being down and its long open edge up, means for pouring body material into said trough through the long open top edge thereof, a drier to receive the board after it leaves pouring position, and means intermediate of the board forming means and the drier for cutting and turning the board from an upright to a horizontal position.
4. Apparatus for making wall board with foamaceous material which comprises means for folding a strip of covering material into a continuous forwardly travelling narrow trough, means for supporting said trough in upright position, its long closed edge being down and its long open edge up, means for pouring body material into said trough through the long open top edge thereof, and

means for supplying a protective covering for the edge of the body at the open end of the trough.

5. Apparatus for making wall board with foamaceous material which comprises means for folding a strip of covering material into a continuous forwardly travelling narrow trough, means for supporting said trough in upright position, its long closed edge being down and its long open edge up, means for pouring body material into said trough through the long open top edge thereof, and means for providing a recess at the open edge of the trough between the sides of the covering material on the body of the board.

6. Apparatus for making wall board with foamaceous material which comprises means for folding a strip of covering material into a continuous forwardly travelling narrow trough, means for supporting said trough in upright position, its long closed edge being down and its long open edge up, means for pouring body material into said trough through the long open top edge thereof, means for providing a recess at the open edge of the trough between the edges of the covering material on the sides of the board, and means for depositing a protective material in said recess to seal that edge of the board.

7. Apparatus for making wall board with foamaceous material which comprises means for folding a strip of covering material into a continuous forwardly travelling narrow trough, means for supporting said trough in upright position, its long closed edge being down and its long open edge up, means for pouring body material into said trough through the long open top edge thereof, means for providing a recess at the open edge of the trough between the edges of the covering material on the sides of the board, means for depositing a protective material in said recess to seal that edge of the board, and means for smoothing the protective material after it is deposited.

CALEB PAYNE.
